United States Patent Office.

WILLIAM H. EMMONS, OF NEW YORK, N. Y., AND FRANKLIN KISSAM, OF NEWARK, NEW JERSEY.

Letters Patent No. 96,094, dated October 26, 1869.

IMPROVED BURGLAR-ALARM.

The Schedule referred to in these Letters Patent and making part of the same.

Be it known that we, WILLIAM H. EMMONS, of the city, county, and State of New York, and FRANKLIN KISSAM, of the city of Newark, county of Essex, and State of New Jersey, have invented a new and useful Improvement on Alarms for Safes, Vaults, Banks, and Buildings, which we call a Burglar-Detector; and we do declare that the following is a full, clear, and exact description of the construction and operation of the same, reference being had to the annexed drawings, forming a part of these specifications.

Figure 1 shows an outside view of top, front, and right-hand side of the alarm or detector, in imitation of a pile of books.

Figure 2 is a section of fig. 1.

a represents a section of plates of glass, forming an inside case or box.

b, the outside case.

The other letters, described elsewhere, represent one method of arranging springs, cords, or wires, and levers, so as to let off the alarm.

Figure 3 shows a section of a side elevation.

a', section of bell.

b', the stand or post to which the bell is attached.

j, hollow shaft or pipe, with arms or levers.

k, pipe.

The dotted line, the spring driving the clock or alarm-movement, the different parts represented by the letters *c*, *d*, *e*, *f*, *g*, and *h*.

Figure 4 is a section of a front elevation.

c', the spring.

e', grooved pulley.

g', cord, for winding up clock or spring-movement, one end wound around pulley *e'*, the other end attached to ring *h'*.

The other letters are the different parts of a common clock-alarm movement.

The outside case, seen in fig. 1, and in sections in figs. 2, 3, and 4, marked *b*, can be made of any suitable material, as hardened-steel plates, chilled cast-iron, or common cast-iron, in almost any ornamental shape or form, as a pile of books or bee-hive.

The inside case, *a*, shown in figs. 2, 3, and 4, in sections, should be made of thin glass, so as to break readily. It might be blown in the shape required, or plates can be cemented together.

The object of the glass case is to insure the sounding of the alarm, by the breaking of glass on one side, in case the outer case be tampered with by means of a drill or hammer.

In fig. 2 is shown one method of arranging springs, cords, and levers, so as to cause the alarm to sound in case the glass be broken.

c, the springs, which can be made of brass, steel, or rubber, are fastened to glass case at *e*, by cementing, or by drilling small holes through the glass, and putting end of spring through and doubling and twisting, the other end running up through a ring at *f*, thence to and connecting with collar *g*, between the levers *h* and *i*, the levers moving on pins marked

j. At *e* are fastened cords or wires, *d*, running through *f* to *g*. On the opposite side are supposed to be cords and springs, arranged the same, also connecting at *g*. Now if one side of the glass be broken, the springs on the opposite side will draw the collar *g* toward it, moving one of the levers *h* or *i*, which will move or free the alarm-catch, thus causing the alarm to sound.

The position of the springs and cords or wires will have to be varied, according to the size of the bell and its location. Where convenient, they can run straight from one side to another, and by the use of angled levers, any side can be connected with the alarm or levers in any position.

The alarm or detector can be placed on the outside of buildings, to call policemen or arouse neighborhoods; it can be made to strike certain times, as a clock, or it can be put inside on safes, or connected with vaults, to frighten robbers and awake janitors.

In connecting it with a safe, a hole must be drilled through the top of the safe, the detector placed on top, the pipe *k*, figs. 3 and 4, passing through the hole, the lower arm or lever is then fastened to shaft *j*. A catch is placed on the door of the safe, which, on the door being shut, catches the arm *j*. On opening the door, the arm is moved, and the alarm sounded. The sides of the safe can be protected in a similar manner to that described for the glass case.

The spring or clock-movement is wound up from the inside of the safe or vault, by means of the cord *g'*, wound around and fastened to the pulley *c'*, and running through hole *i* in shaft *j*, and attached to ring *h'*. The cord is pulled to wind up the spring. We thus avoid the danger of a key-hole.

Perforations can be made in outer as well as inner case, so as to allow the sound to escape more freely, care being taken to not allow the openings, which must be small, of the outer to be near those of the inner case.

We do not claim, as original, an alarm sounded simply by means of springs; neither do we claim the operation of winding a clock by means of a cord and pulley; but

What we do claim as our invention, is—

1. An inner casing of glass, to which the alarm is connected by cords or wires secured to it, so that upon the breaking of the glass, the alarm is sounded, and protected by the outer case, as shown and described.

2. In combination with the above, the hollow shaft, protected by the pipe, passing through a safe, and connecting the alarm with the door-lock or sides of the safe, and allowing the alarm to be wound up from the inside of the safe, or vault, or room, to which it may be attached.

WM. H. EMMONS.

Witnesses: FRANKLIN KISSAM.
